SLUG CASTING MACHINE

William L. Petersen, Springfield, N. Y., assignor
to Mergenthaler Linotype Company, a corpora-
tion of New York

Application May 26, 1937, Serial No. 144,839

20 Claims. (Cl. 199—47)

This invention relates to slug casting machines, such as Linotype machines of the general organization represented in United States Letters Patent to O. Mergenthaler, No. 436,532, wherein in a melting pot is arranged to deliver molten melt into a slotted mold and up against a composed line of matrices to produce a type bar or slug bearing on its edge type characters corresponding to the intaglio characters of the matrices. In these machines, the molten metal is introduced into the mold by means of a spring-actuated pump piston or plunger arranged within the pot and controlled in its action by a rotary cam which, as well known, makes one complete rotation for each cycle of operation of the machine. The cam is so shaped as normally to maintain the pump plunger in a raised position out of action, but at one portion of its circumference it is formed with a depression which at the proper time permits the plunger to descend under the influence of its actuating spring to force the metal into the mold, it being understood in this connection that the distance the plunger descends or its effective stroke is largely determined by the amount of metal it displaces rather than by the depth of the depression in the cam. Since the slugs produced in the modern machines vary widely in size (both as regards length and thickness), it is evident that the effective stroke of the plunger will vary correspondingly, assuming, of course, that the metal be kept at a constant level within the pot. Thus, when casting short slugs of the thinner variety, the plunger descends only a short distance as compared with the distance it is required to travel when casting long slugs of the thicker variety. In practice it has been found that this variable condition frequently leads to the casting of defective slugs. The difficulty is that oftentimes the actual casting period is too short to permit the molten metal to congeal or solidify before the return stroke of the pump plunger, which, under such circumstances, exerts a suction effect and draws some of the metal from the mold back into the pot. The condition becomes more aggravated in the case of the larger slugs which, not only require a greater volume of metal and therefore a greater time for cooling, but which in addition necessitate a longer effective stroke of the pump plunger and correspondingly less time before it begins its return stroke.

The present invention is intended to overcome these and other objections and contemplates automatic means for delaying the return stroke 55 of the pump plunger for a predetermined inter-

val after the mold has been filled with molten metal to allow additional time for the metal to solidify before the pump pressure is removed. In the present embodiment, the machine is equipped with a driving pinion and a driven gear mounted on the cam shaft, the driven gear having a mutilated portion which arrives opposite the driving pinion as the depression in the pump plunger cam (which permits the active stroke of the plunger) arrives in operative position. The result is that the driving pinion ceases to drive the cam shaft, thus permitting the pump plunger to pause for a definite period at the end of its active stroke. The duration of this pause is determined by a segmental gear which overlaps the mutilated portion of the driven gear and which in turn is adapted to mesh with and be driven by the driving pinion. Normally, the segmental gear is carried along by the driven gear, but when the mutilated portion of the latter arrives opposite the driving pinion, the driving pinion then engages the segmental gear and causes the latter to rotate through a limited arc, allowing the main driven gear to remain stationary temporarily. Thereafter, an abutment on the segmental gear engages the driven gear and causes the latter to rotate until the mutilated portion thereof is carried past the driving pinion, enabling the latter again to actuate the driven gear. As the segmental gear passes out of the range of the driving pinion, a detent effects its arrest momentarily until it is again picked up by the driven gear through the engagement of a portion of the latter with an abutment on the segmental gear. The segmental gear is spring-held in this position (which is its normal one) with respect to the driven gear during the completion of the machine cycle and until it is again actuated in the succeeding machine cycle. In other words, the segmental gear has a limited degree of lost motion relative to the driven gear, and it is this lost motion which determines the extent of the pause during which the pump plunger is allowed to remain at the bottom of its active stroke.

The invention also contemplates means for varying the extent of the lost motion of the segmental gear and consequently the duration of the pause for slugs of different sizes. It will be understood that for small slugs, no pause in the operation of the machine is necessary, and accordingly means are provided for coupling the segmental gear in such cases to the driven gear, so that the rotation of the latter will be con-

tinuous or uninterrupted throughout the casting cycle.

In the accompanying drawings, the invention has been shown merely in preferred form and by way of example as applied to a Linotype machine, but obviously many changes and alterations may be made therein and in its mode of adaptation without departing from its spirit. Generally speaking, it is to be understood that the invention is not limited to any specific form or embodiment, except insofar as such limitations are specified in the appended claims.

Referring to the drawings:

Fig. 1 is a side elevation, partly in section, of the casting mechanism constructed in accordance with the invention, and showing the parts in their normal position of rest;

Fig. 2 is a side elevation of the driven gear and segmental gear assembly, showing the parts in a position wherein the mutilated portion of the driven gear has arrived opposite the driving pinion;

Fig. 3 is a view similar to Fig. 2, but showing the parts in a position wherein the segmental gear is engaging the driven gear to move the mutilated portion of the latter past the driving pinion;

Fig. 4 is a view similar to Fig. 2, but showing the parts in a position wherein the segmental gear has moved past the driving pinion and has been brought to rest;

Fig. 5 is an elevation of a portion of the mechanism shown in Fig. 4, and illustrating the parts immediately after the driven gear has picked up the segmental gear for the completion of the machine cycle;

Fig. 6 is a transverse vertical sectional view on line 6—6 of Fig. 3; and

Fig. 7 is a sectional view on line 7—7 of Fig. 2.

In Fig. 1, the parts are shown in the relative positions they occupy just prior to the commencement of the slug casting operation, the slotted mold A carried by the rotary disc A¹ being closed at the front by the composed line X, which is presented momentarily thereto by the first elevator B, and at the rear by the mouthpiece of the melting pot C, which contains a supply of type metal maintained in a molten condition by means of a suitable burner or heater (not shown). The pot C is formed with a throat or passage C¹ through which the molten metal is forced into the mold by a spring-actuated plunger D, the latter being arranged to reciprocate within the pot well or cylinder C² communicating with the throat C¹. The plunger D is connected by means of a rod or link D¹ to the long arm of a bell-crank lever D² having a sleeve portion D³ journalled on a fixed transverse rod D⁴ of the machine frame and provided with an arm D⁵ extending laterally beneath a second lever D⁶, which is also journalled on the rod D⁴ and connected at its free end to a pull spring D⁷. The latter is anchored to the machine frame and actuates the plunger D through the connections just described. The shorter arm of the bell-crank D² is provided with a roller D⁸ arranged to track upon the periphery of the usual rotary cam D⁹ fast to the main shaft of the machine. As well understood, the peripheral face of the cam D⁹ is concentric throughout, except at one portion of its circumference where it is cut away or formed with a depression D¹⁰. When the machine is at rest, the roller D⁸ is in contact with the concentric portion of the cam D⁹, so that the plunger is maintained in its raised or

inoperative position, as shown in Fig. 1. This condition obtains until the casting period arrives, when the cam rotating in the direction indicated brings the downwardly sloping surface d of the depression D¹⁰ into engagement with the roller D⁸, which then quickly descends along such surface toward the bottom of the depression, thus permitting the spring D⁷ to depress the plunger and force a charge of molten metal into the mold. As the cam continues to rotate, the roller D⁸ is engaged sooner or later by the upwardly sloping surface d¹ of the depression D¹⁰, and the parts thereby more gradually restored to their original condition to await the next casting operation.

The parts so far described, and their construction and mode of operation, are or may be the same as those embodied in the commercial Linotype machine and in themselves constitute no part of the present invention.

It will be understood that, during the slug casting period, the roller D⁸ will ordinarily seldom reach the bottom of the depression D¹⁰, due to the fact that the plunger D will be arrested in its descent at one level or another according to the volume of metal it displaces in effecting the cast. The shape of the depression D¹⁰, it will be observed, provides for no dwell of the roller D⁸ therein, except insofar as the distance through which the roller enters the depression causes a delay in the engagement of the roller by the sloping surface d¹ of the cam which effects the ascent of the pot plunger, and this delay, indeed, will be shorter, the larger the slug cast, since the deeper the roller D⁸ enters the depression D¹⁰, the sooner will the sloping surface d¹ commence the ascent of the plunger. The result is that for the larger slugs, the pump plunger D starts to ascend before the metal has congealed in the mold A, and consequently sucks some of the metal from the mold back into the melting pot, thus producing imperfect slugs. In accordance with the present invention, it is proposed to delay or effect a pause in the ascent of the pump plunger D, so as to give the metal sufficient time to congeal properly in the mold, this delay or pause being effected in the instant case by arresting the operation of the machine—and hence the rotation of the cam shaft—as the plunger begins its active stroke.

Before describing the mechanism for effecting the pause just referred to, it might be stated that, as usual, the main shaft M of the machine on which the pump plunger cam D⁹ is mounted, is rotated by a driving shaft M¹ through the medium of a driving pinion M² fixed thereon and a driven gear M³ fast to the main shaft M. Ordinarily, during each machine cycle of operation, the driven gear M³ is rotated continuously throughout a single rotation of the cam shaft M. According to the present improvements however, this gear, in a sense, is mutilated to the extent that it has a portion M⁴ where three of the gear teeth are missing and, when this mutilated portion arrives adjacent the driving pinion M², which incidentally occurs when the roller D⁸ arrives opposite the depression D¹⁰ in the cam D⁹, the rotation of the driven gear M³ ceases and, after a given pause, to allow for the cooling of the slug, restarted, so that the machine cycle of operation can be completed. The driven gear restarting mechanism includes devices which operate to move the mutilated portion M⁴ of the driven gear M³ past the driving pinion, so that the driven gear again meshes therewith.

The restarting mechanism, just alluded to, in-

cludes a segmental gear N (see Fig. 6) freely mounted on the main shaft M and arranged for rotational movement relative to the driven gear M³. The outer portion of the segmental gear is offset, so as to bring its peripheral edge adjacent the peripheral edge of the driven gear, and it is provided with gear teeth likewise arranged to mesh with the teeth of the driving pinion M², the latter being made somewhat longer than usual for this purpose.

In the normal position of the parts (see Fig. 1), the segmental gear N, at its leading end, overlaps the mutilated portion M⁴ of the driven gear M³ and is in advance of the driving pinion M², this position being determined by an adjustable screw N¹ threaded through a lug N² screwed to one face of the segmental gear and abutting against a spacing sleeve E¹, which forms part of the means which secures the cam assembly E to the driven gear M³. These respective positions of the segmental gear N and the driven gear M³ are maintained by a tension spring N³ partially encircling the hub of the segmental gear and anchored at one end to said gear and at its opposite end to one of the cams of the cam assembly E.

Shortly after the slug casting operation is started, the depression D¹⁰ in the cam D⁹ arrives opposite the roller D⁸, permitting, as previously stated, the plunger D to descend under the action of its spring D⁷ to force metal into the mold. Simultaneously therewith, the mutilated portion M⁴ of the driven gear M³ arrives opposite the driving pinion M², i. e., in the position shown in Fig. 2, whereupon the rotation of the main shaft M ceases. At this time, however, the segmental gear has meshed with the driving pinion and, although, as before noted, the driven gear is now stationary, the rotation of the segmental gear continues in the direction indicated by virtue of the lost motion connections between the two.

The segmental gear N continues its rotation alone until it reaches the position shown in Fig. 3, wherein a set screw N⁴, which is threaded into a lug N⁵ projecting from the face of the segmental gear opposed to that which presents the abutment N² (see Fig. 6), engages one of the spokes of the driven gear M³. It will be noticed that the engagement of the spoke of the driven gear by the screw N⁴ occurs before the teeth at the trailing end of the segmental gear N leave the driving pinion M², so that, as the driving pinion continues to rotate the segmental gear, the latter will, through the devices just described, restart the rotation of the driven gear M³, to move the mutilated portion M⁴ thereof past the driving pinion. The rotation of the driven gear thereupon continues, being now driven directly by the pinion until the machine cycle of operation is completed.

As the segmental gear N passes beyond the driving pinion M², its motion is arrested (see Fig. 4) by the engagement of a spring-pressed 65 detent O, arranged in a bracket O¹ fixed to the machine frame, in a recess N⁶ presented in the bottom face of the lug N² in which the abutment N¹ is threaded, and this position of the segmental gear is maintained until the continued rotation of the driven gear M³ brings the sleeve E¹ into engagement with the abutment N¹ (see Fig. 5). Thereupon, the segmental gear N is carried along with the driven gear M³, the detent O being moved out of the recess N⁶, this function being readily accomplished as a result of the relative

configurations of the recess and the detent at its outer end. It might be stated here that the detent O includes a large head portion O² slidably arranged in a long cylindrical recess O³, and a smaller portion O⁴ encircled by a compression spring O⁵ reacting between the head of the detent and the base of the recess, said smaller portion extending through the base of the recess and having a plurality of nuts O⁶ threaded thereon, by means of which the upper end of the detent can be properly located. It might also be stated that the lug N² on the segmental gear is provided with a bevelled surface N⁷ which engages the detent and serves to depress the same, so that it will ride beneath the lug and enter the recess N⁶ in the bottom thereof as the segmental gear N is moved to the position shown in Fig. 4.

The length of the segmental gear N and the degree of lost motion between it and the driven gear M³ are such as to create a sufficient pause in the casting cycle to allow even the largest slugs properly to congeal in the mold and, for slugs of different sizes, the duration of the pause can be regulated by the adjustment of the set screw N⁴, since obviously different adjustments of the set screw will vary the degree of relative movement between the segmental gear and the driven gear. The various adjustments of the set screw N⁴ are maintained by a lock nut N⁸. The banking screw or abutment N¹ is also adjustable, so as to insure perfect alinement between the teeth of the segmental gear and the teeth of the driven gear; the adjustment of this screw likewise being maintained by a similar lock nut N⁹.

It will be understood that when casting small slugs, the pause in the casting cycle will not be necessary and, for this reason, mechanism is provided for coupling the segmental gear N and the driven gear M³ together in their normal positions, wherein, as previously stated, the segmental gear overlaps the mutilated portion M⁴ of the driven gear and, when the gears are thus coupled, the machine will operate in the normal way. The coupling means (see Figs. 2, 6 and 7) includes a pin P mounted in the segmental gear and arranged to be moved transversely thereinto of into a hole M⁵ formed in the driven gear M³ and which registers with the pin when the segmental gear and the driven gear are in their normal relative positions. When the pin is moved toward the right from the position shown in Fig. 6 into the hole M⁵, the two gears are coupled together and will act as a unitary driven gear, the teeth of which are continuous or uninterrupted throughout its periphery. The different positions of adjustment of the coupling pin P are maintained by a spring-pressed detent P¹ arranged to engage in one or another of a pair of recesses P² in the pin, depending upon its position of adjustment. The adjustment of the pin is effected through the medium of a knurled headed screw P³, which passes through a slot P⁴ formed in the end of the segmental gear, the slot being long enough to permit the adjustment, just mentioned, to be made. The screw P³ is threaded transversely into the coupling pin and prevents the pin from turning, so that the recesses P² therein will always be in alinement with the spring-pressed detent. It will be observed that the pin P, in its end opposite that adjacent the driven gear, is cut away, but this is merely for the purpose of clearing certain of the machine parts during the rotation of the segmental gear.

Having thus described my invention, what I claim is:

1. In a slug casting machine, the combination of a mold, a pump plunger for filling the mold with molten metal under pressure, and automatic means actuated at different periods independently of the pump plunger for delaying the return stroke of said plunger after the mold has been filled with molten metal to allow additional time for the metal to solidify before the pump pressure is removed. 10
2. In a slug casting machine, the combination of a mold, a pump plunger for filling the mold with molten metal under pressure, and automatic means actuated at different periods independently of the pump plunger for creating a pause in the operation of the pump plunger after its mold filling stroke to allow additional time for the molten metal to solidify before the pump pressure is removed. 15
3. In or for a slug casting machine embodying a main cam shaft, driving means for said shaft comprising a driving gear, a mutilated driven gear fast to the cam shaft, and a segmental driven gear having a limited lost motion with respect to the mutilated gear and overlapping the mutilated portion thereof. 20
4. In or for a slug casting machine embodying a main cam shaft, driving means for said shaft comprising a driving gear, a mutilated driven gear fast to the cam shaft, and a segmental driven gear having a limited lost motion with respect to the mutilated gear and overlapping the mutilated portion thereof, the extent of the lost motion being variable to correspondingly vary the period of interruption in the rotation of the driven gear. 25
5. In or for a slug casting machine embodying a main cam shaft, driving means for said shaft comprising a driving gear, a mutilated driven gear fast to the cam shaft, a segmental driven gear having a limited lost motion with respect to the mutilated gear and overlapping the mutilated portion thereof, and a spring tending constantly to hold the segmental gear in its normal position with respect to the mutilated gear. 30
6. In or for a slug casting machine embodying a main cam shaft, driving means for said shaft comprising a driving gear, a mutilated driven gear fast to the cam shaft, a segmental driven gear having a limited lost motion with respect to the mutilated gear and overlapping the mutilated portion thereof, a spring tending constantly to hold the segmental gear in its normal position with respect to the mutilated gear, and a yielding detent to hold the segmental gear temporarily in a stationary position at the end of its lost motion stroke. 35
7. In a slug casting machine, the combination of a mold, a pump plunger for filling the mold with molten metal under pressure, and automatic means for creating a pause of definite duration in the return stroke of the pump plunger after the mold has been filled irrespective of the extent of its mold filling stroke. 40
8. In or for a slug casting machine embodying a main cam shaft, driving means for said shaft comprising a driving gear, a mutilated driven gear fast to the cam shaft, and a segmental gear having a limited lost motion with respect to the mutilated gear, said segmental gear acting to move the mutilated portion of the driven gear past the driving gear after the lost motion between the mutilated gear and the segmental gear has been taken up. 45

9. In or for a slug casting machine embodying a main cam shaft, driving means for said shaft comprising a driving gear, a mutilated driven gear fast to the cam shaft, a segmental gear having a limited lost motion with respect to the mutilated gear, and means on the segmental gear acting to engage the driven gear to move the mutilated portion thereof past the driving gear after the lost motion between the mutilated gear and the segmental gear has been taken up. 10

10. In or for a slug casting machine embodying a main cam shaft, driving means according to claim 9, wherein the means on the segmental gear are adjustable to vary the degree of lost motion between the mutilated gear and the segmental gear. 15

11. In or for a slug casting machine embodying a main cam shaft, driving means for said shaft comprising a driving gear, a mutilated driven gear fast to the cam shaft, a segmental driven gear having a limited lost motion with respect to the mutilated gear and overlapping the mutilated portion thereof, and means for coupling the segmental gear and the mutilated gear together when a continuous drive of the cam shaft throughout a casting cycle is desired. 20

12. In or for a slug casting machine embodying a main cam shaft, driving means for said shaft comprising a driving gear, a driven gear fast to the cam shaft and having a mutilated portion adapted to arrive opposite the driving gear at an intermediate stage of the machine cycle so as to effect a pause in the rotation of the cam shaft, and means acting automatically and after a predetermined period to move the mutilated portion of the driven gear past the driving gear so as to restart the rotation of the cam shaft to complete the machine cycle. 25

13. In a slug casting machine, the combination of a mold, a pump plunger for filling the mold with molten metal under pressure, operating means therefor, and automatic means independent of the pump plunger for stopping and restarting the plunger operating means at different periods after the pump plunger has begun its mold filling stroke and before the machine has completed its normal cycle. 40

14. In a slug casting machine, the combination of a mold, a pump plunger for filling the mold with molten metal under pressure, operating means therefor, and automatic means independent of the pump plunger for stopping the plunger operating means during the effective stroke of the pump plunger and for restarting it at a later predetermined period. 50

15. In a slug casting machine, the combination of a mold, a pump plunger for filling the mold with molten metal under pressure, operating means therefor, and driving means for the machine, said driving means including devices operative automatically and independently of the pump plunger to stop and restart the plunger operating means at different periods after the pump plunger has begun its mold filling stroke and before the machine has completed its normal cycle. 60

16. In a slug casting machine, the combination of a mold, a pump plunger for filling the mold with molten metal under pressure, operating means therefor, and driving means for the machine, said driving means including devices operative automatically and independently of the pump plunger to stop the plunger operating means during the effective stroke of the pump 70

plunger and for restarting it at a later predetermined period.

17. In a slug casting machine, the combination of a mold, a pump plunger for filling the mold with molten metal under pressure, and driving means for the machine, said driving means including devices operative automatically at different periods independently of the pump plunger to establish a pause in the operation of the pump plunger.

18. In a slug casting machine, the combination of a mold, a pump plunger for filling the mold with molten metal under pressure, operating means therefor, and driving means for the machine, said driving means including devices operative automatically at different periods independently of the pump plunger to establish a pause in the operation of the plunger operating

means sufficient to delay the return stroke of the pump plunger after the mold has been filled with molten metal.

19. In or for a slug casting machine embodying a main cam shaft, driving means including devices operative automatically at different periods independently of the pump plunger to establish a pause in the rotation of the cam shaft at a predetermined period in and before completion of its normal cycle of operation.

20. In or for a slug casting machine embodying a main cam shaft, driving means including devices operative automatically at different periods independently of the pump plunger to establish a pause in the rotation of the cam shaft during and before completion of the casting cycle of the machine.

WILLIAM L. PETERSEN.
